HINGE

Charles R. Suska, Roxbury, Conn., assignor to The Stanley Works, New Britain, Conn., a corporation of Connecticut

Filed Aug. 31, 1966, Ser. No. 3,670

Term of patent 14 years

(Cl. D10—9)

FIG. 1

FIG. 2

FIGURE 1 is a side elevational view of a hinge;
of the hinge;

above of one of the caps thereof; and

low of one of the caps thereof.

The dominant feature resides in the hinge barrel caps
as shown.

I claim:

The ornamental design for a hinge, as shown and described.
